RADIO RECEIVER VOLUME CONTROL
CIRCUIT

James C. Coe, Arlington, Va.

Application October 16, 1940, Serial No. 361,357

12 Claims. (Cl. 179—1)

(Granted under the act of March 3, 1883, as
amended April 30, 1928; 370 O. G. 757)

This invention relates specifically to volume controls for radio receiving apparatus, it being an object of the invention to provide a system whereby the output level of various loads connected in parallel across the output terminals of a receiving or amplifying device may be individually adjusted, within certain limits, without affecting the output level of the other loads connected thereto.

It is a further object of this invention to provide a system whereby adjustment of the volume control to various loads connected in parallel across the output terminals of a receiving or amplifying device may be independently made for each load, without materially affecting the total impedance across the output terminals.

In the type of installation to which this specification particularly relates, the adjustment of the volume of one of the loads such as a speaker or headset, will affect the volume of the other speaker or headset loads connected in parallel therewith. In such an installation it is nearly impossible, particularly when many loads are provided, to maintain the output level in one load constant, without continual adjustment. It is an object of this invention to overcome the above disadvantage or difficulty encountered in this type of installation by providing a means coincident with the operation of the volume control means which will change the receiver or amplifier output to accommodate the increase or decrease in output level.

This is accomplished in the control to one headset by an adjustable attenuating resistor or network which is connected between the receiver output and the headset, and is combined mechanically with a receiver gain or sensitivity control, which may take the form of a variable resistor which may be connected in the cathode circuit of certain tubes of the receiver, although other means for controlling the sensitivity, known in the art, may be provided; a second and similar arrangement applies to the second control of a second headset and includes an adjustable attenuating resistor or network between the receiver output and the second headset, this resistor or network being mechanically connected to a variable resistor which is connected electrically in parallel with the receiver gain or sensitivity control resistor of first control.

In the embodiment illustrated there is shown a device which provides means for obtaining individual control of the output of a radio receiving apparatus to two loads such as headsets. The output to one headset can be adjusted by

means of one control to any desired level between extremes, and the output of the other headset can be set by means of the control to any desired level between extremes, also the output level in one headset may be radically different from that in a second headset. Having once established the desired level in the two headsets by means of the two controls, if any change in the output level to one headset becomes desirable, it may be accomplished without producing any appreciable effect upon the level in the second headset.

With the foregoing and other objects in view, the invention consists in the construction, combination and arrangement of parts hereinafter described and illustrated in the drawing, in which:

Fig. 1 is a wiring diagram showing the connections for a plurality of headsets connected in parallel to the output terminal of a radio receiving set;

Fig. 2 is a wiring diagram showing a modification of the connections illustrated in Fig. 1, wherein the total impedance across the output terminal remains substantially constant for all adjustments.

In the circuit shown in Fig. 1, R₁ is a series variable resistance connected between the receiver output terminals and the headset load H₁. R₂ is a variable resistor connected to terminals leading to the receiver cathode circuit. The two resistance elements R₁ and R₂ are each provided with an adjustable arm. These arms are mechanically coupled but electrically insulated so that moving the control of one resistance element in a direction to short out more resistance will also cause the arm of the other resistance element to move in a direction shorting out more of its resistance. Thus with less resistance between the headset load H₁ and its receiver output, the load drawn by the headset H₁ is increased. To supply this increase in load under normal conditions of operation, well below the receiver overload condition, the resistance R₂ connected to the terminals leading to the receiver cathode circuit is also decreased, thereby increasing the receiver sensitivity or gain. In the embodiment illustrated by Fig. 1, there is also connected in shunt across the receiver output terminals a second headset load H₂. This headset load also has connected in series therewith a variable attenuating resistor R_a. The variable resistance R_b is connected to the terminals leading to the receiver cathode circuit. The resistance R_a and R_b are both pro-

vided with an adjustable arm. These arms are also mechanically but not electrically coupled so that movement of one arm to increase or decrease the resistance of one element will cause a similar increase or decrease in the other resistance element, as is apparent from Fig. 1 and the description set out above.

The change in setting of the resistor to HS₁ will have a slight effect upon HS_a, due to the change in receiver sensitivity or gain caused by the change in the resistance in the receiver cathode circuit. This change will, however, be small when compared to the change produced upon headset load HS₁, because R₁ is primarily applicable to headset HS₁ and is only secondarily applicable to headset HS_a, and because the receiver output regulation effects the change in the output voltage as it varies with the load, and the load varies with a change in R₁.

Readjustment of the control to headset HS_a may, under some conditions, be necessary to obtain proper output level, particularly if the changes in R₁ and R₂ have been relatively large.

More than two loads may be used, each with its control consisting of units similar to R_a and R_b or R₁ and R₂. As explained above, the movement of a control to change the volume level in that headset produces some change in the volume level to the other headsets, but the greatest change will be produced in that one headset where it is desired. One control may be set to give maximum response in its headset, another control may be set to give a much lower response in its headset, and the remaining controls may be set for intermediate or extreme values of volume level to their respective headsets. Adjusting the power level to one headset to a low value does not prevent the other headsets from obtaining higher lever, or adjusting the level to one headset to a maximum value below overload does not prevent the other headsets from having their levels set to lower values by means of their controls. If one control is set to give a maximum response in the corresponding load, it is still possible to obtain a lower level of response in the second load because of the attenuation available in the audio circuit between the receiver output and that load. In other words, the receiver may be operated at a high sensitivity and low audio attenuation to one headset, and at a low power level in the second headset due to audio attenuation between the receiver output and the second headset.

If this device is used in moving vehicles such as airplanes, a certain amount of change of level in one headset only secondarily incidental to a greater change of level produced in another headset may not be serious enough to require readjusting the level to the first headset, but an extreme change in the level to one headset may require readjusting the level to the other headset somewhat, in order to maintain the proper value.

Fig. 2 differs from Fig. 1, in that a more complex type of control circuit is used between the receiver output and each headset, i. e., the simple series resistance R₁ of Fig. 1 is replaced in Fig. 2 by a network composed of resistances R₁, R₂ and R₃. Similarly, the resistance R_a has been replaced by resistances R_a, R_b and R_c. The impedance of this network combined with the impedance of its associated headset is more nearly constant than the series resistor headset combination of Fig. 1, although it is not necessarily an absolutely constant impedance net

work. It has been found from actual practice that a maximum variation in the impedance of the combination of HS₁, R₁, R₂ and R₃ of the order 3 to 1 may in some installations be entirely satisfactory, and will not produce an effect appreciably noticeable to the ordinary hearing in the other headsets.

In Fig. 2, headset loads HS₁ and HS_a are connected in shunt across the output terminals of the receiver. The variable resistances R₃ and R_c are each shunted directly across their respective headsets, namely, HS₁ and HS_a.

The value of the resistance elements R₃ and R_c is determined largely from the characteristics of the headsets HS₁ and HS_a. If the impedance ratio of R₃ to HS₁ is too high, control characteristics will not be smooth, since the impedance of the network would vary greatly with different settings of the control, while if this ratio is too low, an excessive amount of incoming power from the receiver output would be wasted in heating resistance R₃, similarly with R_c. The proper impedance ratio is determined between these extremes to give the best engineering compromise between fairly constant impedance and waste of power.

The headset loads HS₁ and HS_a each have connected in series therewith a mesh circuit comprising the resistance R₁, R₂, R₃ and R_a, R_b, R_c, respectively. The resistance elements R₁ and R₃, as well as R_a and R_c, are variable, each being provided with an adjustment arm. These arms are electrically and mechanically connected together so that as R₁ is increased an increasing portion of the resistance R₃ is connected in a branch of the mesh circuit including the resistance R₂ and in series with resistance R₁. A circuit can also be traced from the receiver output in shunt across the headset HS₁ and includes a portion of resistance R₁ and a portion of the resistance R₃ not connected in the aforementioned mesh circuit.

The variable resistance elements R₄ and R_d are each connected to the terminals leading to the receiver cathode circuit. Each resistance element has an adjustment arm associated therewith, the adjustment arm of R₄ being mechanically but not electrically connected to the adjustment arms of R₁ and R₃, so that as the resistance of the mesh circuit which is in series with the headset HS₁ is increased, the resistance R₄ in the cathode circuit of the receiver or amplifier is also increased. The adjustment arm for resistance R_d is also mechanically but not electrically connected to the adjustment arms for resistance elements R_a and R_c.

In the position of maximum power delivered to headset HS₁, for example, the adjustment arms of resistance elements R₁, R₃ and R₄ are in their extreme clockwise position providing a shunt path shorting out the resistance elements R₁ and R₂, leaving only HS₁ and R₃ in parallel; in this position the resistance element R₄ in the cathode circuit is also shunted. The impedance of such a combination may readily be determined by means of computations known to the art.

In the position of the control for minimum power into HS₁ the impedance of the network consisting of HS₁, R₁, R₂ and R₃ can be determined by considering the group consisting of HS₁ and R₃ in parallel, and this group in series with R₂, then with R₁ in parallel with the aforementioned series parallel combination in order to obtain the impedance of the aforementioned group. The impedance of such a network may

be determined by means of computations known in the art. It is also to be noted that in this position the resistance element R4 is inserted into the cathode circuit decreasing the receiver sensitivity or gain.

With any intermediate setting for power available to either headset HS1 or HSa1, the impedance of the group consisting of HS1, R1, R2 and R3, or HSa, Ra, Rb and Rc, may be calculated by applying Kirchhoff's laws, by means well known in the art.

Fig. 2 has the advantage over Fig. 1 in that the load on the receiver output is relatively constant, regardless of the setting of the controls. Changing the setting of one control affects the signal level in the other headset due to change in receiver sensitivity, but this change in the second headset is much less than that produced in the first headset where the change is desired.

It should be clearly understood that in Fig. 2 resistors Ra, Rb and Rc perform the same function with respect to HSa as resistors R1, R2 and R3 perform with respect to HS1.

While my invention has been described above in connection with a radio receiver having a cathode circuit for sensitivity control, it is obviously applicable for use in connection with other receiving devices for electrical communications having sensitivity control circuits employing variable resistances. Loud-speakers and headsets are only two of the many types of sound reproducing devices that may be employed.

Other modifications and changes in the number and arrangement of the parts may be made by those skilled in the art without departing from the nature of this invention within the scope of what is hereinafter claimed.

The invention described herein may be manufactured and/or used by or for the Government of the United States of America for governmental purposes without the payment of any royalties thereon or therefor.

Having thus set forth and disclosed the nature of this invention, what is claimed is:

1. In a control circuit of a radio receiving apparatus, the combination including, a sound reproducing device, an audio attenuator control therefor, a receiver sensitivity control, and means mechanically connecting the attenuator and sensitivity control together so that upon adjustment providing a decrease in the attenuation, the receiver sensitivity is increased.

2. In a control circuit of a radio receiving apparatus of the type having a controllable cathode circuit therein, the combination which includes, plural sound reproducing devices, control means for at least one reproducing device permitting the adjustment of the output level of said device, and means coincident with the adjustment of said output control means preventing said adjustment from materially affecting the output level to said other reproducing means, said last named means including a variable resistor connected to the cathode circuit of said receiving apparatus.

3. In combination, a radio receiving apparatus having an output circuit, plural sound reproducing devices connected thereto, means for varying the volume of said reproducing devices while still maintaining the total impedance across the output circuit substantially constant, and means operative with the adjustment of said volume control means for affecting the sensitivity of the receiving apparatus.

4. In a radio receiving apparatus having a

cathode circuit, a pair of output terminals, a plurality of loads comprising sound reproducing devices connected in parallel across said output terminals, a variable attenuating resistor connected in series with at least one of said load devices, terminals leading to the cathode circuit of the receiving apparatus, a variable resistor connected to said terminals, adjustable contact arms for both of said resistors, said arms being mechanically connected together, whereby the adjustment of one variable resistance will also effect adjustment of the other variable resistance.

5. In combination, a plurality of sound translating devices, a common audio frequency supply means for said translating devices having a cathode circuit, lines connecting said devices to the common audio frequency supply means, a pair of terminals leading to the cathode circuit of said audio frequency supply means, a variable resistor connected to said terminals, a variable attenuator for at least one sound translating device comprising a plurality of impedance elements, one of said elements being variable and connected in shunt directly across the sound translating device, the other of said elements comprising a mesh circuit connected in series with the translating device, said mesh circuit including a fixed and a variable impedance element, the variable impedance element connected across the translating device and the variable impedance element of the mesh circuit each having adjustable contact arms, said arms being mechanically connected together so that in one extreme position the mesh circuit impedance is shorted out, and means responsive to the adjustment of said contact arms which will change the resistance connected to said cathode circuit.

6. In combination, a plurality of sound translating devices, common audio frequency supply means for said device having a cathode circuit, conductors connecting said devices to the common output terminal of said common source of audio frequency, a pair of terminals leading to the cathode circuit of the audio frequency supply, a variable resistor connected thereto, a variable attenuator for at least one sound translating device, said attenuator comprising two variable resistors and a fixed resistor connected in the output circuit of the supply means, and means coincident with the adjustment of the variable attenuating resistors which varies the resistor connected in the cathode circuit.

7. In combination, a plurality of sound reproducing devices, common audio frequency supply means therefor having a cathode circuit, means connecting said devices to the output terminals of said audio frequency supply means, means permitting independent control of the output level to each of the sound reproducing devices without materially changing the total impedance offered by said reproducing device and its control means, said means comprising three variable resistors connected together mechanically, two of said resistors being connected in the output circuit between the audio supply and the sound reproducing devices, the third variable resistor being connected in the cathode circuit of the audio supply.

8. In a control circuit of a radio receiving apparatus the combination including, a sound reproducing device, an audio attenuation control therefor, a receiver sensitivity control means, and means mechanically connecting the attenuation control and receiver sensitivity control means to-

gether so that upon adjustment providing for a decrease in the attenuation, the sensitivity is increased.

9. In a radio receiving apparatus, the combination including an output circuit, plural sound reproducing devices connected in parallel across said terminals, means comprising an adjustable resistance network for varying the volume of said reproducing device from a maximum to a minimum without producing a variation in the impedance of said reproducing device and network greater than 3 to 1, and means operative with the adjustment of said volume control means for controlling the sensitivity of said radio receiving apparatus.

10. In an electrical communication system having an output circuit and a sensitivity control circuit, a plurality of sound reproducing devices connected in parallel with said output circuit, variable attenuating means connected in the output circuit of at least one reproducing device, said means permitting the adjustment of the attenuation to said reproducing device without pro-

ducing any effect appreciably noticeable to the ordinary hearing in the other headset, a variable resistance element connected in the sensitivity control circuit, and means operative with the adjustment of the variable attenuation means for varying the variable resistance to change the sensitivity of said system.

11. In a receiving device for electrical communications, an output circuit, a reproducing device connected thereto, an adjustable attenuating means for said reproducing device, and separate means operative with said attenuating means for varying the sensitivity of said receiving device.

15 12. In a receiving device for electrical communications, an output circuit, plural reproducing devices connected thereto, an adjustable attenuation means for at least one said reproducing device, and separate means operative with said attenuating means for varying the sensitivity of said receiving device.

JAMES C. COE.
